VARIABLE GUN CHOKE

Joseph C. Hilburn, Cedartown, Ga.

Application June 27, 1947, Serial No. 757,443

1 Claim. (Cl. 42—79)

1

The present invention relates to variable gun chokes and it consists in the combinations, constructions and arrangements of parts herein described and claimed.

It is an object of the present invention to provide an attachment which may be quickly and easily adapted to a gun barrel and which will provide a variably adjustable choke therefor.

Another object of the invention is the provision of an adjustable choke for shot guns and the like wherein provision is made for the escape of gasses when the gun is fired.

A further object of the invention is the provision of an adjustable choke for shotguns wherein provision is made for a forward sight for the gun.

A further object of the invention is the provision of means whereby very fine adjustments may be made in an adjustable choke for shot-guns and the like.

Other and further objects of the invention will become apparent from a reading of the following specification taken in conjunction with the drawings, in which:

Figure 1 is a plan view of an embodiment of the invention,

Figure 2 is a vertical sectional view of Figure 1,

Figures 3, 4 and 5 are elevational views of elements of the invention,

Figure 6 is a sectional view taken along line 6—6 of Figure 4, and

Figure 7 is a sectional view taken along line 7—7 of Figure 2.

Generally, the invention provides a device which may be readily attached to the barrel of a shotgun and comprising three principal parts, namely, a choke sleeve adapted to be threadably attached to the nozzle of a shotgun and having a plurality of longitudinally extending slots in its forward end, an actuating sleeve threadably engaged with the choke sleeve and an adjusting sleeve threadably engaged with the actuating sleeve and having a tapered inner face adapted to engage the outer end of the choke sleeve to move the slotted portions thereof inwardly. Provision is made for a forward sight to be carried by the adjusting sleeve which sight is provided with an inwardly extending detent adapted to engage in one of the slots whereby the sight will be held against rotary motion when the choke is adjusted.

Referring now more particularly to the drawings, there is shown therein a gun barrel 10 to which is threadably connected, as indicated at 11, the internally threaded rear end of a choke sleeve

12 which is provided at its outer end with a plurality of longitudinally extending slots 13 and with a tapered forward end 14.

Integrally formed in the choke sleeve 12 adjacent the rear end thereof is a gas escape cylinder 15 having a plurality of spaced internally formed annular grooves 16 each having a plurality of spaced openings 17 interconnecting the same and the outer periphery of the cylinder 15.

10 Forwardly of the cylinder 15, the choke sleeve 12 is provided with a right-handed externally threaded portion 18 which is adapted to engage the internally threaded portion 19 of the rear end of an actuating sleeve 20 which is provided centrally with a left-handed externally threaded portion 21 and whose forward end is provided with a series of longitudinally extending slots 22 and which is exteriorly tapered, as indicated at 23. The actuating sleeve 20 is provided with a knurled portion 24 adjacent the rear end of the same.

An adjusting sleeve 25 is internally threaded, as shown at 26, and is adapted to engage the threaded portion 21 of the actuating sleeve 20 and is provided with a tapered forward end 27 having a flattened step 28 formed therein, the inner side of the step 28 being adapted to engage the forward untapered portion of the choke sleeve 12.

30 A split ring 29 of spring material is adapted to lie in an annular groove 30 formed exteriorly in the actuating sleeve 20 and forwardly of the knurled portion 24 thereof. The ring has formed integrally therewith a detent 31 which is adapted to extend inwardly through an appropriate opening in the actuating sleeve and engage in one of the slots 13.

In the step 28 there is affixed a front sight 32 which is provided with an inwardly extending dog 33 which is adapted to positively engage in a

40 groove 13.

In operation, it will be apparent that by revolving the actuating sleeve in one direction by placing the fingers upon the knurled portion 24 thereof, that the actuating sleeve will be caused to move rearwardly and the adjusting sleeve likewise will be caused to move rearwardly. When the actuating sleeve is revolved in the opposite direction, the same will move outwardly from the barrel 10 and outwardly upon the choke sleeve 12 and, at the same time, the adjusting sleeve 25 will be caused to move outwardly of the choke sleeve.

During these movements, the inner end of the detent 31 will be moved from one to another of the slots 13 latching but not locking the actuating

sleeve to the choke sleeve and at the same time producing an audible clicking noise to advise the user as to the amount of adjustment he is using.

Also, at the same time, the dog 33, being permanently engaged in a slot 13, will prevent revoluble movement of the adjusting member 25 and thus the front sight 32 will remain permanently aligned with the rear sight of the gun. During these movements of the actuating sleeve 20, the forward and rearward movement of the adjusting sleeve thus caused will cause the tapered end 23 to come into contact with the inner side of the tapered portion 27' of the adjusting sleeve, thus causing the forward end of the choke sleeve to contract, due to the pressure of the underside of the forward end of the actuating sleeve thereon. At the same time, the tapered end 14 of the choke sleeve will come into contact with the inner side of the tapered portion 27 and be caused to contract. Thus, two elements cause the contraction of the forward end of the choke sleeve and a consequent changing of the pattern of shot propelled from the gun. The grooves 16 and openings 17 provide for the escape of the gases of combustion when the gun is fired.

While but one form of the invention has been shown and described herein, it will be readily apparent to those skilled in the art that many minor modifications may be made without departing from the spirit of the invention or the scope of the appended claim.

What is claimed is:

A device of the character described comprising a tubular choke sleeve having its rear end portion internally threaded for removable engagement with a gun barrel, said sleeve having its front end externally tapered and being formed with longitudinally extending circumferentially

spaced slots leading from its front end, a portion of the sleeve rearwardly of the slots being formed with right hand threads, an actuating sleeve fitting about the choke sleeve and having its rear end portion internally threaded for engagement with the right hand threads of the said choke sleeve, the actuating sleeve having its front end externally tapered and being formed with longitudinally extending slots leading from its front end and rearwardly of its slots having a portion formed externally with left hand threads, an adjusting sleeve fitting about the choke sleeve forwardly of the actuating sleeve and having internal threads in its rear portion engaging the left hand threads of the actuating sleeve and its forward portion internally tapered for applying compressing pressure to the slotted forward portion of the choke sleeve when the adjusting sleeve is shifted rearwardly by rotation of the actuating sleeve, and a front sight carried by the adjusting sleeve and having a portion projecting into the adjusting sleeve and engaged in a slot of the choke sleeve to prevent turning of the adjusting sleeve about the choke sleeve.
